UNITED STATES PATENT OFFICE.

ELVYN FREMONT BURRILL, OF BERKELEY, CALIFORNIA.

FLYING MACHINE.

Application filed August 10, 1923. Serial No. 656,627.

To all whom it may concern:

Be it known that I, ELVYN FREMONT BURRILL, a citizen of the United States, residing at Berkeley, in the county of Alameda and State of California, have invented a new and useful Flying Machine, of which the following is a specification, wherein my invention is so fully and clearly disclosed as to enable anyone skilled in the art to make and use the same.

My invention relates to that type of flying machines which have the power of vertical as well as horizontal flight, and also the power of varying the magnitude of the vertical, or lifting thrust, by small degrees so as thereby to vary the rising or falling speed at will, and to attain stationary, or hovering flight.

The mechanisms combining in a machine of this character fall naturally into three groups: (1), the fundamental, or lifting and driving mechanism; (2), the voluntary controls for effecting rising, falling, and hovering, and for changing from vertical to horizontal flight and vice versa; (3), the automatic safety devices for easing the machine to the ground in case of failure of the power.

The principal object of the present invention is to provide a flying machine of the highest possible flexibility, universal in its directional capacity, adapted to carry a single flyer and sufficiently small and light to be responsive in its directional controls to leanings or small sliding movements of the pilot's body, so that it might not inaptly be called a powered flying bicycle.

A further object is to work intrinsically into the structure the highest degree of safety possible without resorting to separate and weight producing devices for that purpose.

It is well understood that the main reason for the small progress as yet made in this field is the lack of a propelling mechanism of adequate power and efficiency. Accordingly it is my central and most important object to provide such adequate propelling mechanism.

So formidable, however, are the inherent difficulties of vertical flight and so different from those involved in flight as at present developed, that vertical flight is as yet a new and practically unknown art. Furthermore, on account of the absence hitherto of any scientific statement of these difficulties

and of the principles involved, and since they are inseparably connected with and must dictate the aerodynamic character of any mechanism designed for their solution, it will be proper to explain, in a general way, the fundamental difficulty before proceeding to the specific mechanism.

In the case of the aeroplane, the propeller is called upon to perform but one twentieth to one tenth of the total work of sustaining the plane in the air, while in a machine for vertical flight the propeller must perform the total work of sustentation. Thus, it is seen that however admirable the aeroplane propeller is for its purpose, it is essentially a light duty instrument.

Given an aeroplane requiring a fifty horse power engine and propeller just to sustain it in level flight; to lift the same plane vertically would require an engine and propeller, if of the same form, of five hundred horse power, and this without counting the greatly increased weight of the engine and propeller. To overcome this increased weight, a still further augmentation of the power would be necessary, and so there ensues a critical race between the ever increasing weight and the increased power necessary to overcome it.

Thus it is evident that mere lightness becomes a prime object and of the essence of the invention, and this must be accompanied by such aerodynamic power and efficiency as only the most rigorous attention to economy can evolve. Consequently all the elements entering into my machine contribute to these two objects, in order that it may be able to perform its basic function, namely, lifting its load.

There exists but one general type of mechanism for this purpose which possesses these two prime requisites in an adequate degree. This mechanism is sometimes called generically a turbinaero. It is in principle the converse of the aeroturbine as exemplified in the steam turbine, whose power and efficiency are well known. When the common rotary tangential fan is used as the generating element, the turbine-aero possesses the highly important property that, while the rotational velocity remains constant and the dimensions are increased proportionally, the generated aerodynamic power increases as the fourth power of the dimensions while the weight increases only as the cube of the

dimensions; so that as the dimensions are increased the lifting power outruns the weight. One form of symmetrical or double turbinaero is embodied in a patent issued to me Nov. 15, 1921, Patent No. 1,397,400; and the present invention involves the same instrument in a modified form.

The general arrangement and effect of this mechanism may be best understood by reference to the skeleton Fig. 7 accompanying; which is merely a conventional figure for explanatory purposes, and may be regarded as a cross section of an imaginary apparatus. In Fig. 7 *a*, *b*, *c*, *d*, represent the vanes of a pair of tangential fans, rotating in the vertical plane in opposition as indicated by the arrows. These fans when rotating uncovered in the open air generate an aerodynamic power in the form of an infinitude of tangential force lines equally dispersed all around the peripheries, and the coordinate sum of these force lines is, of course, zero. By a well known mechanical principle, corresponding reactions take place about the fan pivots and the sum of these reactions is also zero. Assuming the vanes to be flat or nearly so and the force lines strictly tangential, since the vanes strike the air with an angle of incidence of 90°, the quantity or magnitude of aerodynamic power per unit area is the greatest possible to the science; and conversely, the area and therefore the weight per dynamic unit is the smallest possible. Now when the directors or guide planes *PP*, and *P'P'* are placed in relation to the fans as shown, the dispersed circular and therefore neutralized force lines are collected and combined in their totality into a solid vertical dynamic, the downward thrusts, or actions, impinging on the stationary air, and the reactions forming an upward thrust under the crowns of the planes. While this takes place, the reactions about the pivots remain algebraic zero, so that there are no hostile or downward thrusts communicated to the mechanism through the pivots, and there results a net lift equal to the total generated aerodynamic power. Since as stated above the generated dynamic is the greatest possible, it follows that the resulting lift is also the greatest possible per unit of prime power.

How important an element of power is involved in this combination may be further amply illustrated from hydrodynamics and especially from hydraulics. It is well known that when a force stream, such as a stream of water from a nozzle, impinges upon a concave or other surface so as to be turned from its original direction by the concave, a motive force is imparted to the concave, the amount and direction of which depend

upon the turning angle. If such turning angle is 90°, the direction of the imparted motive force is at right angle to the original direction of the stream, and its amount is unity, that is, equal to the total force residing in the stream. If the turning angle is 180°, so that the stream is turned completely back upon itself, the imparted motive force is in line with the direction of the stream, and its amount is double the force residing in the stream.

Reverting now to the Fig. 7, it will be seen that the aerodynamic stream having its initial point at vane *a*, is turned by the concave *P* back upon itself, or through 180°, and therefore impresses a lift under the plane double its own initial force. The stream having its initial point at vane *b* is turned 90°, thus impressing a lift under the plane equal to its own inherent force. Vane *c* receives a unity lift of reaction directly upon itself which is communicated to the mechanism through the pivots. The stream with initial point at vane *d* is received by plane *P'* and turned downward 90°, thus impressing unit lift under that plane. It can be demonstrated both mathematically and experimentally that the lift of this system is substantially equal to the total generated aerodynamic power.

Having thus laid the ground of basic principles, my apparatus will be understood as a whole and in detail by reference to the accompanying drawings, in which: Fig. 1 is a side view of the double turbinaero, showing a vane of the purely tangential fan, in which case the vane is straight.

Fig. 2 is a rear end view with fuselage removed showing the internal and general structure.

Fig. 3 is a side view showing the slightly helical vanes and with a portion of the upper guide plane broken away to show position of pilot's seat when slightly rearward of the center and machine careened rearwardly a few degrees in the attitude of purely vertical flight.

Fig. 4 is a side view showing pilot's seat in central position and the mechanism on level keel in attitude of horizontal flight.

Fig. 5 is a top or plan view with planes removed showing organization of the power and transmission system.

Fig. 6 is a detail of the engine sheave showing the method of ratchet and pawl engagement with the engine spindle.

Fig. 7 is a diagrammatic sectional view showing the directions of air currents in operation.

Referring first to the supporting member, 1, Fig. 2, is the base which is the chief stiffening member of the whole system, and carries the engines. It is preferably built in a box-like form of light ply construction.

Somewhat above the base at either end and fixed to it by upright supporting struts are lateral spars, 2, reinforced by the curved braces 3, the whole forming an approximately triangulated bracing system. Since the direction of flight is transverse of these spars, they are streamlined in cross section. Upon these spars, at suitable distances from their ends, are fixed clamps 4, for holding 10 the ends of tubes 5, which extend lengthwise through the center of the fan axles 6, and upon which they turn. These tubes also serve as fixed struts or spacers for the spars, and since they are subject only to small 15 linear strains, may be very thin and light. At the ends of the tubes, just inside the clamps, where are located the bearings of the fan axes, the tubes may be reinforced with solid cores. Upon the tubes are mounted 20 the long fan axes 6. These are hollow and of considerable diameter to resist the large torsional strains. They are built up of successive layers of ply wood so as to be very strong and light. At their ends are inserted 25 hard wood disks bored out in the center to receive the bearings which turn on the tubes above described.

The rims of the large fan sheaves 9^a and 9^b are preferably made of sheet duraluminum having the grooves for the driving cables rolled in, which construction has the greatest strength and lightness. These rims are firmly mounted upon the axes by means of bicycle or other system of spoking. The 35 two sheaves are not set exactly opposite each other but are staggered half the width of the rims in order to align with their respective engine sheaves as shown.

Upon the tubular axes 6, on either side of 40 the sheaves and at suitable intervals along their length, are fixed radial arms 7, for supporting the vanes 8 of the fans. These may be light wood trusses, each comprising a pair of thin strips coupled together in 45 parallel at their ends and spread in the middle to embrace the large axes.

The vanes 8, which may be as many as found most suitable, (four are here shown), 50 may be made of wood veneers, duraluminum or other suitable material. The vanes are parted midway of their length to provide space for the driving sheaves and clearance for the cables.

Above and about the fans are mounted 55 the cylindroidal directors or guide planes 10, Figs. 1 and 2, upon whose under surfaces is impressed the aerodynamic power generated by the fans. These planes are preferably made of thin duraluminum and may be 60 supported in position in any approved manner, as by light wood curved trusses, not necessary to further describe. It is important, however, to give careful attention to the curves in order to secure the highest dynamic

efficiency. This is especially true of the curvatures at the entering and trailing edges in reference to the air streams. Since the magnitude of the thrusts due to impact and reaction under the crowns of the planes depends upon the volume and velocity of the 70 air streams, it is necessary to make the entering curvature such that the streams may impinge with a glancing blow and so be eased into the concave without injury to their velocities. At the trailing edges there 75 are presented conditions similar to those at the stern of a yacht, where the lines must be so designed as to prevent dragging swirls and to secure a clean parting of the water from the curved surfaces. So in the present 80 case, after the entering streams have been turned through a full 180°, and issue downward from under the planes, these should depart by slight degrees, in the latter portion of their curve, from true circularity so 85 as to secure a gradual parting with the falling vanes of the fans. For the rest the curve is circular and may be as close to the path of the vane tips as consistent with safe clearance. The planes should be polished 90 on their under surfaces to reduce air friction.

Through the lower arc of rotation it is manifest that the tangential force lines are spread out fanwise and exert a lifting effect 95 by reaction under the vanes until the vanes in succession approach the lower vertical position, when the tangents approach the horizontal and so lose their lifting effect. In order to utilize these lower horizontally 100 tending force lines and to turn them downward, the planes 11, 11 are provided. Through the turning reaction of these lines a lift is exerted under these planes. In all 105 these operations the air enters at the vacant core and is thrown outward by centrifugal force to the peripheries.

Planes 11, 11, in addition to performing approximately one fourth of the total lift, 110 also perform another very important function. On account of the great flexibility designed in the present machine, it becomes necessary to endow it with a wider range of variability of lift than heretofore provided, the reason for which will appear later in 115 the specification. These planes are hinged along their upper edges so as to be swung manually in and out as shown by the solid lines and dotted lines, in Fig. 2, indicating their varying positions. The manner in 120 which they accomplish the variability of lift is as follows: When the planes are retired to their extreme positions back to back as shown by the solid lines, they contribute their maximum quota to the lift; when they are gradually opened outward the lift is diminished because the force lines strike them with a head-on collision as shown by 125

the double arrows and their velocity is destroyed; when they are opened outward to the extreme positions shown by the light dotted lines, the force lines impinge upon their tops and thus exert a depressing effect. Thus the variability extends from maximum lift through all gradations, including zero lift, to a considerable depression on the negative side. The requisite movements are accomplished by means of a hand control wheel 22^a on the pilot's control board, similar to the steering wheel of an automobile, which operates a system of cables attached to the planes, all of which control system is well known and needs no further description.

The specification thus far has dealt with the strictly aerodynamic elements of my invention. Since this form of lifting and flying mechanism is a pioneer in the field of aeronautics, not hitherto known or used, I do not limit myself to the precise forms and mechanisms herein described, but reserve freedom to employ other means provided they accomplish the same results. For instance in the case of planes 11, 11, just described, it is evident that they might be fixed at their lower edges while their upper edges swing downward. In such case as their upper edges progressed downward they would cease to turn the air streams from the lower inward striking vane downward, and said streams would impinge upon their tops, and so substantially the same results would be accomplished as that indicated in the drawings.

This principle holds also in regard to the shape of the fan vanes. In Fig. 1 I have shown the vanes as straight while Figs. 3 and 4 show them having a slight helical curve. If I make the vanes straight so that the force lines are strictly tangential, the machine is still a vertical flying machine and I am privileged to employ any of the horizontal propellers now in use to drive it forward after it has risen into the air under its vertical propellers.

But I prefer, for the sake of simplicity and lightness, to incorporate an axial thrust intrinsically in the fans. This I do by giving the vanes a slight helical curve similar to the blades of a lawn mower, as shown in Figs. 3 and 4, since the direction of flight is axial to the fans. The degree of the helical curve is such that only a minor component of the total thrust is diverted to horizontal propulsion, since the major thrust must always be reserved for the far heavier work of sustentation.

Coming now to the directional controls, these involve the manner of securing rising, falling and hovering, and changing from vertical flight to horizontal and vice versa. To accomplish these results, I place the pilot

upon a sliding seat, 22, mounted slidably upon the runners 23, in a manner similar to the seat of a racing shell. The small fore-and-aft movement of the seat along the runners is controlled by a pedal operating a sprocket gear of a well known character which needs no special description. By this means the center of gravity is moved longitudinally and the mechanism is thereby caused to careen slightly backward, or to rest on even keel, according as the pilot slides a few inches in either direction along the runners, or occupies a central position.

Assuming now wings 11, 11 to be retracted to their extreme inward position, back to back, and the machine consequently exerting its maximum lift, since there are both axial and tangential thrusts, it is clear that the direction of flight will be obliquely upward, provided the pilot occupies the central position and the machine is on level keel. If now the pilot wishes to secure purely vertical flight, he slides a few inches backward along the runners, when the mechanism will assume the attitude shown in Fig. 3. It is seen that in this attitude the axial thrust is directed slightly upward of the horizontal as shown by the axial arrow. The circular, or lifting thrust, is at the same time inclined slightly backward of the vertical as shown by the rearward of the two upward pointing arrows, Fig. 3. Both of these effects conspire to set up a resistance to forward movement and to produce a purely vertical resultant shown by the strictly vertical arrow. When the pilot has attained his desired altitude he returns to the central position and the mechanism returns to even keel when the axial thrust becomes strictly horizontal as shown in Fig. 4, and there will be forward movement. If the pilot wishes to secure purely horizontal flight, he will gradually reduce the lift by opening out wings 11, 11 until the lift just balances gravity when the movement will be purely horizontal.

It is well known that a body moving horizontally weighs less than when stationary, as manifested by the vertically downward pull, and the greater the horizontal velocity the less the weight. In consequence of this fact the machine will have a tendency to climb as it gets up forward speed. This may be counteracted by opening wings 11, 11 more and more as speed is increased, and thus an even altitude may be maintained. Conversely, when the forward speed is lessened wings 11, 11 must be gradually retracted to prevent loss of altitude. It will thus be evident that wings 11, 11 provide a sufficient variability

of lift for most purposes and above all they provide a sufficiently precise adjustment of the lift to attain an exact balancing of gravity which is necessary to secure a stationary

or hovering condition of the mechanism. When a large or sudden change of lift is desired in order to secure a quick climb or descent, this may be attained by manipulating the engine speed, though this method is not sufficiently exact for the nice adjustments.

I have previously stated that I contemplate a machine of so small a total weight that it will be sensitive to small movements or leanings of the pilot's body. Thus when the pilot wishes to swerve to the right or left of the straight course, he needs only to lean to the right or left, which movement will displace the center of gravity laterally and cause the machine to careen to one side thus introducing a lateral thrust when the machine will swerve to that side to which the pilot leans.

But whatever care one might take to secure extreme lightness in the aerodynamic elements, it would be futile if he were limited to the engines generally in use in aeroplane flight. Just as aeroplane flight had to await the development of an engine of sufficient lightness and efficiency, so vertical flight has awaited still further refinements in these directions. The majority of the engines now in use, weighing from three to six or more pounds per horse power, can develop an aerodynamic power scarcely more than sufficient to lift themselves and the external mechanism without useful load. There exists, however, a type of engine, recently developed, which is of so vital importance to the whole art of vertical flight, and so highly adapted to my present purposes that a brief account of its basic characteristics is required. This is the double rotary type, as yet little known, in which radially disposed cylinders rotate in one direction and the crank shaft in the opposite direction. The effective speed is the sum of these two speeds. There results a high engine speed, which means high power, attended with only moderate absolute speeds of the rotating elements. This fact allows the engine to be constructed with far thinner sections and of lighter materials than is possible with other types. It has been proven feasible to produce an engine of moderate capacity with a weight-power ratio of unity, that is, one pound per horse power. On this basis the saving in engine weight alone provides a sufficient lifting margin for my purposes.

I shall now show how I incorporate this type of engine in my double turbinaero to produce a vertical flying machine of hitherto unattainable lightness and at the same time of the highest safety. A pair of engines, 12, Fig. 5, are mounted head to head, centrally of the base, or fuselage, and at the structural center of the total mechanism,

having the sheaves 13, 16 fixed upon their respective and oppositely rotating cylinder cases and turning normally as a unit with them; and sheaves 14, 15 mounted upon their respective and oppositely rotating crank spindles, and normally rotating with them; an exception will be noted later in connection with the manner of their engagement with the fan sheaves. Thus it is seen that the four engine sheaves 13, 14, 15, 16, rotate in alternate opposition, and with as close clearance as possible. This arrangement causes the center of gravity to coincide with the structural center and neutralizes gyroscopic effects, thus securing good balance and easy turning control in the horizontal plane.

The engine sheaves are engaged with the fan sheaves by means of two endless cables, which are preferably thin woven linen cords, which are wound alternately over the grooves of the engine sheaves and fan sheaves in the following manner: Beginning at an outer groove of fan sheave 9^a, shown as the lowest one in Fig. 5; and at the bottom, the cord is brought up around the outer sector to the top; the cord passes thence to the outer groove, beneath engine sheave 16, thence around to the top of the sheave, thence to the second groove beneath fan sheave 9^a, thence up around the sheave and again to the second groove beneath engine sheave 16, and thus around and around in a spiraloid winding until all the grooves of sheave 16 are filled and one half the grooves of sheave 9^a. The cord is now at the top of sheave 9^a, thence it passes directly to the outer groove beneath fan sheave 9^b as shown in Fig. 2. The cord is brought up around sheave 9^b, thence to the first groove beneath engine sheave 15, around to the top of the sheave, to the second groove beneath sheave 9^b, around to the top of the sheave and so continued until all the grooves of sheave 15 are full and half the grooves of sheave 9^b. The cord is now at the top of sheave 9^b; thence the two ends of the cord, namely the end at the bottom of sheave 9^a and the end at the top of sheave 9^b, are brought down and spliced around the automatic take-up pulleys 12^a, which serve to align the last strand from the staggered first halves of sheaves 9^a and 9^b, and to equalize the tension on all the strands. The windings of the other and entirely separate cord around the other halves of sheaves 9^a and 9^b, and engine sheaves 13 and 14, are precisely similar but in the opposite direction, that is beginning at the outer grooves and proceeding inward.

I have illustrated but one of several styles of winding the driving cable which might be employed. Three important results accrue from this system of drive and trans-

mission. It will be noted that the winding results in a web of strands inter-crossing between the engine sheaves and fan sheaves. This gives approximately a three quarter circumference of traction engagement around the engine sheaves, which gives great positiveness of drive. The strands will not rub at the crossings because of the spiraloid windings. It yields a driving and transmission system of extreme lightness and strength. Last and most important of all, it binds the two rotating members of each engine and all the four rotating members of both engines into a unified system, equalizing the load and the velocities of all the engine sheaves. It will be further noted that both engines participate equally in the drive of both fans, the significance of which in relation to the problem of safety will presently appear. In this connection it becomes necessary to revert more specifically to the mountings of the engine sheaves upon their respective spindles and sleeves. The sheaves are not inflexibly fixed upon the spindles, but the method of mounting will be made clear by reference to the detail Fig. 6. In the figure 16^a is a sleeve cast integrally upon the cylinder case and turning upon the crank spindle 15^a. Upon this sleeve and against the face of the cylinder case is fixed a ratchet wheel 17. Against the ratchet wheel and upon the sleeve 16^a is mounted the sheave 16 which is provided with pawls 18 engaging the ratchet wheel 17, so that sheave 16 is forced to turn as one with the cylinder case. Upon spindle 15^a, which extends beyond the end of the above described sleeve, is fixed a similar ratchet wheel, and adjacent to this is mounted sheave 15, also provided with pawls engaging the ratchet wheel, and so forced to turn under the drive of the crank spindle 15^a. The remaining pair of sheaves is mounted in a precisely similar manner on the sleeve and spindle of the other engine. I contemplate engines of large reserve power so that in an emergency either engine could nearly sustain the mechanism alone. Now in case one of the engines should become stalled, the live engine will automatically assume the entire load, the sheaves upon the dead engine will be automatically released and free to turn as idlers upon the sleeve of the cylinder case and spindle of the crank shaft, and the stalled engine will thus be automatically cut out of the system. Under these conditions the machine will settle gently to the ground. It is to be further noted that the mechanism is a natural parachute and with both engines dead it still would fall in an upright attitude and with a velocity so retarded as not to be disastrous. The combination of these two features provides a factor of safety not hitherto realized. In fact, since the center of gravity lies con-

siderably below the chief points of support, namely, under the crowns of planes 10, the mechanism possesses inherent stability and whether rising or falling will always maintain even keel:

Since this type of flying machine does not run along the ground, no special landing gear is required. It is, however, desirable to provide some sort of resilient landing wheels to neutralize the small shocks that may occur, and for the further purpose of wheeling the machine around upon the ground. This mechanism may be of any approved character and need not be further described. If desired, pontoons could be provided for alighting on water.

The mechanism having now been fully described, the method of operation is as follows: The machine standing upon its supports, the pilot opens wings 11 to their extreme outward positions. He then primes the engines and turns the throttle to low speed. Standing at one corner of the machine he grasps an outer radial arm of one of the fans and gives it a smart downward thrust, wheretupon the engines start. He then mounts his seat and speeds up the engines. When these are sufficiently warmed up and he is ready to rise, he turns the control wheel retracting wings 11 to their extreme inward position when the machine will rise. Should he wish to rise vertically, he slides backward a few inches when the mechanism will take the attitude shown in Fig. 3 and the upward movement will be purely vertical. When a sufficient altitude has been reached the pilot slides forward to a central position and the mechanism will begin to move forward. As the machine accelerates horizontally, wings 11 must be gradually opened out to prevent climbing. Should the pilot wish to secure a hovering position over an objective, as for taking photographs of some object on the ground, he slides backward slightly, thus introducing a resistance to forward motion, at the same time retracting wings 11 in order to maintain altitude, when by nice adjustments the machine may be brought to a stationary or hovering condition. When the pilot is ready to descend, if the altitude is considerable, he will open wings 11 to their extreme limit when he will fall rapidly until he approaches the ground when he must retract wings 11 thus causing the machine to slow down, and as he nears his objective he may secure any degree of slowness until he gently alights with little or no shock.

Having now elucidated my invention as to its principles, construction and use, what I claim is:

1. In a flying machine, in combination with a pair of vertically and oppositely rotating fans, or generators of aerodynamic

- power, and cylindroidal directors, or guides planes placed above and about said fans, adapted to collect the tangentially dispersed air streams about the peripheries of the fans 5 throughout the lower-inner and upper-inner quadrants, and to turn said streams downward; rigid cylindroidal guide planes placed below and inwardly of the fans, adapted to collect the dispersed lower-hori- 10 zontally tending air streams from the lower arcs of rotation and to turn said streams downward, substantially as specified.
2. In a flying machine, in combination with a pair of vertically and oppositely rotating fans, and cylindroidal guide planes placed above and about said fans, adapted to collect the tangentially dispersed air streams about the inner portion of the peripheries of the fans and to turn said streams down- 15 ward; rigid cylindroidal guide planes placed below and inwardly of the fans, adapted to collect the lower-horizontally tending air streams from the lower arcs of rotation and to turn said streams down- 20 ward; rigid cylindroidal guide planes being swingable manually inward and outward, as and for the purpose specified.
3. In a flying machine, a turbinaero comprising a pair of vertically and oppositely 25 rotating fans; cylindroidal guide planes placed above and about the fans, adapted to collect the upward tending and upper horizontally tending air streams from the inner portions of the peripheries of the fans 30 and to turn said streams downward; and rigid cylindroidal guide planes placed below and inward of the fans, adapted to collect the lower-horizontally tending air streams from the lower arcs of rotation and 35 to turn said streams downward, substantially as specified.
4. In a flying machine, in combination with a pair of vertically and oppositely rotating fans, the vanes of said fans having 40 a helical curve; cylindroidal guide planes placed above and about the fans; and cylindroidal guide planes placed below and inward of the fans, said lower guide planes being swingable manually inward and out- 45 ward; a pilot's seat movably mounted on fore-and-aft runways, said pilot's seat being controllable as to its fore-and-aft position along the runways.
5. In a flying machine, in combination 50 with a pair of vertically and oppositely rotating fans, said fans being provided with sheaves, a power plant comprising a pair of double rotary engines, set head to head, having their axes aligned fore-and-aft of the 55 mechanism, the four spindles of said engines having mounted upon them four driving sheaves rotating in close proximity and in alternate opposition, and driving means connecting said fan sheaves and driving sheaves.
6. In a flying machine, in combination 60 with a pair of opposed vertically rotating fans and a corresponding pair of double rotary engines, said fans and the spindles of said engines being provided with grooved sheaves, a transmission winding comprising 70 endless cords wound in spiraloid formation around the grooves of the fan sheaves and engine sheaves, engaging both engines equally with both fans, and forming webs of strands intercrossing between the engine 75 sheaves and fan sheaves.
7. In a flying machine, in combination with a pair of opposed vertically rotating fans and a pair of double rotary engines, 80 sheaves on the fan axes and on the engine spindles, the combination of endless driving cords wound in spiraloid formation around the fan sheaves and engine sheaves, engaging both engines equally with both fans and forming webs of strands intercrossing be- 85 tween the engine sheaves and fan sheaves, and means for automatically regulating and equalizing the tension on all the strands.
8. In a flying machine, in combination with a pair of opposed vertically rotating 90 fans and a pair of engines, fixed sheaves on the fan axes, loose sheaves on the engine spindles, endless transmission cords wound in spiraloid formation around the fan sheaves and engine sheaves, engaging both 95 engines equally with both fans, and automatic tension regulators; means for engaging the engine sheaves with their spindles and for automatically disengaging the sheaves of either engine and causing them 100 to rotate as idlers upon their spindles.
9. In a universal flying machine, a verti- 105 cal flying machine, comprising, in combi- nation, a pair of vertically and oppositely rotating fans; cylindroidal guide planes placed above and about the fans; cylindroidal guide planes placed below and inward of the fans, said lower guide planes being swingable manually inward and out- 110 ward; a pair of double rotary engines; fixed sheaves on the fan axes, loose sheaves on the engine spindles; endless driving cords wound in spiraloid formation around the fan sheaves and engine sheaves engaging both 115 engines equally with both fans; automatic tension regulators; and means for engaging the engine sheaves with their spindles and for automatically disengaging the sheaves of either engine and causing them to rotate as idlers upon their spindles.
10. A universal flying machine, comprising, in combination, a pair of vertically and oppositely rotating fans, the vanes of said fans having a helical curve; cylindroidal guide planes placed above and about said 120 fans; cylindroidal guide planes placed below and inward of the fans, said lower guide planes being swingable manually inward and outward; a pilot's seat movably mounted on fore-and-aft runways, said pilot's seat 125 130

being controllable as to its position along the runways; a pair of double rotary engines; fixed sheaves on the fan axes, loose sheaves on the engine spindles; endless driving cords wound in spiraloid formation around the fan sheaves and engine sheaves, engaging both engines equally with both

fans; automatic tension regulators; and means for engaging the engine sheaves with their spindles and for automatically disengaging the sheaves of either engine and causing them to rotate as idlers upon their spindles, substantially as specified. 10

ELVYN FREMONT BURRILL.
